CLAIM

The ornamental design for a Kufi hat/handbag, as shown.

DESCRIPTION

FIG. 1 is a perspective view of a Kufi hat/handbag showing my new design in use as a hat;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a perspective view thereof in use as a hand bag; and, FIG. 8 is top view thereof.

The features shown in broken lines in the drawings are environmental matter and form no part of the claimed design.
